UNITED STATES PATENT OFFICE.

ELMER S. SHIMER, OF MILTON, PENNSYLVANIA.

LEAD-PENCIL.

1,396,535.

Specification of Letters Patent. Patented Nov. 8, 1921.

Application filed March 2, 1921. Serial No. 449,127.

To all whom it may concern:

Be it known that I, ELMER S. SHIMER, a resident of Milton, in the county of Northumberland and State of Pennsylvania, a citizen of the United States, have invented certain new and useful Improvements in Lead-Pencils, of which the following is a specification.

My invention relates to an improvement in lead pencils of the variety that hold and support small leads of $1\frac{1}{2}$ " length by $\frac{3}{16}$ " diameter, to facilitate utilizing leads without the necessity of sharpenings. As the lead is worn away on its point and requires adjustment forward, the body of the pencil is turned to the right, the point being held rigid. By a reverse turn of the handle it will enable the lead to be pushed back into the holder for reloading with new lead. In this manner about three leads will give the same service as the average wooden lead pencil, with greater efficiency and less expense. By reason of the saving of many extra sharpenings the pencil itself retains its full length. Inasmuch as the leads are renewable from time to time and the mechanical construction of the parts is very rugged, as a mechanical measure, the pencil is bound to take a step in advance.

The body or holder of this pencil is preferably made of black, hard rubber, or wood, or metal can be used in working out substantial pencils without material change of construction of the internal working mechanism.

It is one of the objects of this invention to popularize the use of lead pencils by placing in the hands of users some efficient pencils at popular prices as all the lead in the pencil is rendered useful by this method whereas fully one-third of a wooden pencil is wasted by reason of its short, unwieldy size.

In the accompanying drawings—

Figure 1 is a longitudinal section of the parts assembled.

Fig. 2 is a side and end view of the outer tube.

Fig. 3 is a side view of the inner tube.

Fig. 4 is a side and end view of the threaded pin, and

Fig. 5 is a side view of the handle.

The inner tube 1, has a small bore 2, therethrough. The end 3, with the enlarged opening is drilled out about $\frac{1}{8}$ of an inch after which the mouth of this enlarged hole

is preferably rolled to reduce its diameter so that the threads of a $\frac{1}{4}$ " tap will receive approximately 4 to 6 threads, the remaining portion of the bore being free of threads but being of larger diameter it will enable the threaded end 4, of the pin 5, to enter the bore of the inner tube 1, controlled only by the few threads at the mouth thereby reducing friction or binding.

The pin 5, with its threaded end 4, is inserted through the threaded end of the inner tube 1, so that the point of the pin enters the central bore backing up the lead, the lead being simply pressed into place from the pointed end of the inner tube 1. The outer tube 6, has a sliding fit over these parts, its beveled end being brought up to the groove 7, formed circumferentially around the inner tube 1, whereupon it is rolled into permanent engagement therewith. The opposite end of the outer tube 6, is provided with a key 8, which projects into the groove 9, formed in the threaded end 4, of the pin 5, the function of which is to cause the pin to turn as the outer tube 6, is turned, while permitting the pin 5, to travel freely endwise.

The foregoing constitutes the working parts of the pencil and when the outer tube 6, is turned on the inner tube 1, the threaded end 4, of the pin 5, will move in or out of the bore 2, in which the lead is held serving to push the lead forward when turned to the right and to make clearance therefor when turned to the left thereby enabling the lead to be inserted or pushed back.

The body portion 10, is in the form of a tube which may be of hard rubber, wood, or metal and which preferably has a general taper at its forward end which merges into the tapering forward end of outer tube 6 and the bore of this body portion is such that the outer tube 6, fits it tightly by frictional contact.

A pencil of this character should serve its user for an indefinite period all the time remaining in good repair by reason of the renewability and interchangeability of parts.

I claim—

1. A pencil including a hollow body or handle, an outer tube secured therein and provided with an inwardly projecting key, an inner tube fitted to turn in the bore of the outer tube, a pin having a threaded portion, said pin adapted to enter and screw into the inner tube, the pin being provided with an

internal groove which receives the key whereby when the handle or body portion is turned with respect to the inner tube the pin is moved endwise in one direction or the 5 other to feed the lead forward or provide clearance for it to be inserted or pushed back in the body or handle.

2. A pencil including an inner and outer tube rotatably connected together, one having an internal projecting key and the other provided with internal screw threads at one end of slightly less diameter than its adjacent bore, a pin having a longitudinally grooved, threaded end, adapted to turn in 10 these threads, the groove constructed and adapted to receive the key whereby the turning of the tubes with respect to each other causes an endwise feed of the pin.

3. A pencil including an inner and outer tube rotatably connected together, one having an internal projecting key and the other provided with internal screw threads at one end of slightly less diameter than its adjacent bore, a pin having a longitudinally grooved, threaded end, adapted to turn in 15 these threads, the groove constructed and adapted to receive the key whereby the turning of the tubes with respect to each other causes an endwise feed of the pin.

causes an endwise feed of the pin, and a body or handle in the bore of which the outer tube is frictionally held, one end of the tube protruding from one end of the body or handle and one end of the inner tube protruding from the end of the outer tube, the 30 said adjacent ends in the form of a general continuous taper.

4. A pencil including an inner and outer tube rotatably fitted together, the inner tube having a circumferential groove into which one end of the outer tube is rolled whereby 40 the two are rotatably connected together, the opposite end of the inner tube having internal threads and the corresponding end of the outer tube having a key projecting inwardly into its bore, a pin substantially fitting the bore of the inner tube and adapted to push the lead inserted in said bore forward when turned in one direction, said pin having threads which fit and turn in the 45 threads of the inner tube, said threaded portion longitudinally grooved to receive the key of the outer tube.

In testimony whereof I hereunto affix my signature.

ELMER S. SHIMER.
